DESIGN FOR A COMBINED CIGARETTE HOLDER, ASHTRAY, AND EXTINGUISHER

Harold E. Ridewood, Victoria, British
Columbia, Canada

Application July 17, 1935, Serial No. 57,698

Term of patent 7 years

To all whom it may concern:

Be it known that I, Harold E. Ridewood, a citizen of the Dominion of Canada, subject of the King of England, residing at Victoria, British Columbia, Canada, have invented a new, original, and ornamental Design for a Combined Cigarette Holder, Ash Tray, and Extinguisher, of which the following is a specification, reference being had to the accompanying drawing, forming part thereof.

Figure 1 is a side elevational view of a com-

bined cigarette holder, ash tray, and extinguisher in an open position, showing my new design;

Figure 2 is a front view with the cover removed;

Figure 3 is a side view;

Figure 4 is a top plan view thereof.

I claim:

The ornamental design for a combined cigarette holder, ash tray, and extinguisher, as shown and described.

HAROLD E. RIDWOOD.
